J. C. GEBHART.
MACHINE FOR MEASURING TEXTILE FABRIC.
APPLICATION FILED JAN. 30, 1919.
1,356,616. Patented Oct. 26, 1920.

UNITED STATES PATENT OFFICE.

JOHN C. GEBHART, OF EAGLE ROCK, CALIFORNIA, ASSIGNOR TO ECONOMETER COMPANY, OF ST. LOUIS, MISSOURI, A CORPORATION OF MISSOURI.

MACHINE FOR MEASURING TEXTILE FABRIC.

1,356,616.

Specification of Letters Patent. Patented Oct. 26, 1920.

Application filed January 30, 1919. Serial No. 273,968.

To all whom it may concern:

Be it known that I, JOHN C. GEBHART, a citizen of the United States, residing at Eagle Rock, in the county of Los Angeles 5 and State of California, have invented new and useful Improvements in Machines for Measuring Textile Fabric, of which the following is a specification.

This invention relates to an improvement 10 in machines for measuring textile fabric of the general type disclosed in my U. S. Letters Patent No. 1,259,389, granted March 12, 1918, and characterized by the provision of a knife for slitting the margin of the goods 15 to indicate the line along which the measured length is to be cut or torn from the rest of the fabric, of an arm for effecting the separation or spacing of the rollers between which the fabric is drawn, one of said rollers 20 functioning as a power roller, and of concentric shafts which carry the knife and the arm, respectively.

The invention is directed more particularly to the arrangement of the knife and its 25 associated elements in the structural combination referred to, and its principal objects are to provide for easy access to the knife for the purpose of renewing or sharpening the same or the stationary blade coöoperating 30 therewith, and also to provide a novel arrangement of guard which normally protects the knife and the stationary blade against damage and which also prevents the 35 knife from causing injury to persons or material adjacent the machine.

According to the invention, the arm for 40 the spacing of the rollers and the parts associated with said arm are located within the main casing of the machine, as in my patent referred to, and the knife and the stationary 45 blade are located externally of said casing but within a housing fitted to said casing and which functions as a guard, the organization being such that the housing may be readily removed, and the knife and the associated stationary blade are conveniently accessible for sharpening or renewal upon the 50 removal of the housing.

An embodiment of the invention is illustrated in the accompanying drawings, wherein:

Figure 1 is a side elevation of a machine in which the features of the invention are incorporated, the housing which incloses the 55 knife and the stationary blade being shown

partly in section and partly broken away to show the locking levers.

Fig. 2 is a detail sectional view on the line 2—2 of Fig. 1.

Similar characters of reference designate 60 corresponding parts in both of the views.

The machine to which the improvements of the present invention are especially applicable includes upper and lower rollers 1 and 2 between which the fabric to be measured is drawn, the upper roller 1 functioning as a power roller for the operation of the measuring instrumentality (not shown). The lower roller 2 is suitably mounted in a carrier 21 which follows the construction 65 shown in my patent referred to, that is to say, said carrier is formed as a pivotally mounted rectangular frame and is urged by a suitable spring (not shown) to a normally elevated position wherein the roller 2 70 is pressed against the roller 1 or against the fabric interposed between it and the roller 1, as shown in Fig. 1. The carrier 21 is arranged within the main casing 17 of the machine, said casing inclosing a frame 18 for 75 the support of certain of the operating parts. The arm 23 by which the carrier is depressed is mounted, within the casing 17, upon a transverse shaft 111, which externally of said casing carries an operating 80 lever 112. The movable knife 22 is mounted on a tubular rock shaft 148 which surrounds the shaft 111 of the arm 23 and externally of the casing carries an operating 85 lever 149. As in my prior patent referred 90 to, an element 24 is preferably employed to prevent a simultaneous operation of the arm 23 and knife 22; said element is pivoted at its rear end for horizontal swinging movement and is normally held centered by 95 springs 150 engaging its pivoted heel portion; at its front end it has a transverse head 151 (shown in dotted lines, Fig. 2) for coöperation with upright arms 152 and 153 mounted on or movable with the shafts 111 100 and 148, respectively, said arms being disposed at opposite sides of the element 24 and having confronting cam faces 154 for engagement with the head 151. The operating levers 112 and 149 are arranged in 105 adjacency and the element 24 prevents their simultaneous operation but enables either of them to be independently operated. Thus, if the lever 112 be depressed to operate the arm 23 and also the carrier 21, the 110

- arm 152, acting on the head 151, will swing the element 24 to project said head across the path of the arm 153, the head thus functioning as a lock for the arm 153 and the parts associated therewith, so long as the arm 23 is held lowered; in like manner, if the lever 149 be depressed to operate the knife 22, the arm 153, acting on the head 151, will swing the element 24 to project 5 said head across the path of the arm 152, the head thus functioning as a lock for the arm 152 and the parts associated therewith so long as the knife 22 is held lowered. If both levers 112 and 149 be pressed simultaneously no operation will result because the head 151, co-acting with their cam faces, will simultaneously lock both of the arms 152 and 153 and the parts associated therewith.
- 10 According to the present invention, the knife 22 and the fixed blade 158 with which it coöperates are mounted externally of the casing 17 but within a housing 155 removably secured to said casing as by fastening screws 156, said housing having a slot 157 registering with the slot 19 of the casing 17, and below said slot carrying the fixed blade 158, preferably secured by screws 159 and with which the knife 22 coöperates, the 15 material to be measured, of course, being drawn through the slots 19 and 157. The knife 22 is preferably composed of a blade 22^a and an arm 22^b to which said blade is secured by screws 22^c, and the arm 22^b has a 20 hub 22^d which is preferably keyed to the shaft 148 so as to turn with said shaft but be removable therefrom; and the blade 22^a is pressed toward the fixed blade 158 by a spring 160 surrounding the shaft 148 and 25 arranged between the hub 22^d and the frame 18. The spring 160 preferably has a seating in a recess or opening 161 formed in the casing 17 concentric to the shaft 148 and is arranged to act torsionally on said shaft or 30 the hub 22^d keyed thereto in order to hold the knife 22 in a normally elevated position and to return said knife and the operating lever 149 to said position after each operation thereof. The levers 112 and 149 are, 35 of course, mounted externally of the housing 155 and are held against endwise displacement from the respective shafts 111 and 148 by a nut 162 secured to the end of the shaft 111. The housing 155 normally protects 40 the blades 22^a and 158 against damage by contact with other objects and also serves as

a safety guard for the protection of the clerk or other person happening to be near the machine, as well as for preventing the knife from catching against and injuring any 60 fabric or other material that may be lying on the counter near the machine. On the removal of the nut 162 and the removal of the housing 155 from the casing 17 the blades 22^a and 158 are readily accessible for 65 the purpose of sharpening or renewal.

I claim—

1. In a machine for measuring textile fabric, the combination of a casing having a slot through which the fabric is drawn, a 70 pair of rock shafts, one of them being tubular and inclosing the other, said rock shafts projecting into said casing, sundry devices operated by said rock shafts within said casing, a housing fitted externally to 75 said casing and through which said rock shafts project, said housing having a slot alining with the slot in said casing, a knife mounted within the housing upon the tubular rock shaft, a stationary blade mounted 80 within the housing for coöperation with the knife, and adjacent operating levers mounted upon the respective rock shafts and disposed externally of the housing.

2. In a machine for measuring textile 85 fabric, the combination of a casing having a slot through which the fabric is drawn, a pair of rock shafts, one of them being tubular and inclosing the other, said rock shafts projecting into said casing, sundry devices 90 operated by said rock shafts within said casing, a housing fitted externally to said casing and through which said rock shafts project, said housing having a slot alining with the slot in said casing, a knife disposed within 95 the housing and having a hub keyed upon the tubular rock shaft, a stationary blade secured to the vertical wall of said housing for coöperation with said knife, a spring 100 acting upon said hub to press the knife toward the stationary blade, and adjacent operating levers mounted upon the respective rock shafts and disposed externally of the housing.

In testimony whereof I have hereunto set 105 my hand in presence of two subscribing witnesses.

JOHN C. GEBHART.
